Patented Jan. 11, 1972

222,846

MINIATURE AIR COMPRESSOR OR THE LIKE

Ryozo Kondo, 972 Tsutsumikata-machi, Ohta-ku,
Tokyo, Japan

Filed May 4, 1970, Ser. No. 22,796

Term of patent 14 years

Int. Cl. D15—02

U.S. Cl. D65—1

FIG. 1

FIG. 2

FIG. 3

FIG. 4

FIG. 5

FIG. 6

FIG. 7

FIG. 1 is a perspective front view of a miniature air compressor or the like embodying my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof; and

FIG. 7 is a top plan view thereof.

I claim:

The ornamental design for miniature air compressor or the like, as shown.
